ROBERT A. GORSUCH, OF GAMBIER, OHIO, ASSIGNOR TO THE CONGOR MFG. COMPANY,
OF GAMBIER, OHIO, A CORPORATION OF OHIO

UNFOLDING CONSTRUCTION FOR BROODERS AND OTHER INCLOSURES

Application filed November 10, 1927. Serial No. 232,262.

This invention relates to an improved container that is especially adapted for use as either or both a shipping box for baby chicks, and a so-called primary brooder, an example of such a device being shown in my Reissue Patent No. 16,518, granted January 4, 1927.

It is the main purpose of my present invention to provide a construction for a device of the aforesaid character that is, initially, in a collapsed or folded condition so that it will occupy a relatively small space, thereby to facilitate storage and shipment of the device in its original form and before it is assigned to its intended use, and that may be readily unfolded and thus conditioned for use, as for the transportation of chicks, and for employment as a brooder.

A further object is to provide a very simple and inexpensive construction through which the foregoing purpose is attained.

Other and more limited objects will appear as I proceed to describe the invention by reference to the accompanying drawings wherein like reference characters designate corresponding parts throughout the different views, and in which Fig. 1 is a perspective view of my improved container or brooder in its initial and unfolded condition; Fig. 2 is a similar view of the container or brooder unfolded and with the side and end walls secured together; Fig. 3 is a vertical longitudinal section through the container with a cover applied thereto; and Figs. 4 and 5 are enlarged sectional details through the connection between the bottom and one of the peripheral walls, and illustrating the manner of bending the edge portion of the bottom wall downwardly so as to dispose the other wall in a vertical position.

For ventilating and cleaning purposes, it is desirable to make the bottom walls of primary brooders of a foraminous material such as wire screen of suitable mesh, and in my present invention a bottom wall 1 of such material is shown. In constructing the container or brooder, peripheral walls consisting of end walls 2 and side walls 3 are layed upon or disposed in sidewise relation to the end portions and the side portions, respectively, of the bottom wall 1, with the outer edges of

the peripheral walls in register with the edges of the bottom wall. Metallic channel members 4 are then engaged over the outer edges of the peripheral walls and the underlying edges of the bottom wall, and are secured thereto as by forming depressions 5 and 6 along the outer and inner sides of the channel members 4.

When in collapsed or folded condition, the peripheral walls may be pressed down to lie very closely to the bottom wall 1 so that the unit is comparatively thin and in this form may be packed for storage or shipment in relatively small space.

When it is desired to unfold and condition the device for use, a suitable tool 8—shown by broken lines in Figs. 4 and 5 and which may be in the nature of a folding brake—is applied to the channel members 4, and the edges of the bottom wall bent downwardly so as to dispose them, and consequently the peripheral walls, in right angular relation to the bottom wall, as shown in Fig. 5. According to the construction illustrated, wherein the side walls 3 overlie the end walls 2 and have inwardly folded end extensions 3^a for a purpose which will presently appear, the edges of the bottom wall to which the side walls 3 are connected are first bent downwardly so as to erect said side walls, after which the end extensions 3^a thereof are folded outwardly at substantially right angles to the body portions of said walls. The ends of the bottom wall may now be bent downwardly so as to dispose the end walls 2 in perpendicular relation to the wall 1, and fastening means, such as wire staples 9, may then engage through the end extensions 3^a and the end walls 2, as shown in Fig. 2. A cover 10, designed to telescope over the peripheral walls, completes the container. The cover 10 and the peripheral walls 2 and 3 are preferably constructed of suitable cardboard or corrugated paper board.

Having thus described my invention, what I claim is:

1. A device of the character set forth comprising a rectangular wire screen bottom wall, peripheral walls consisting of end walls and side walls disposed in sidewise relation

to the bottom wall, the outer edges of the peripheral walls registering with the edges of the bottom wall, a metallic channel member embracing the outer edge of each of the end 5 and side walls and the corresponding edge of the bottom wall and extending substantially the full length thereof, the peripheral walls being adapted to be positioned at right angles to the bottom wall by bending the edge portions of the bottom wall downwardly, certain of the peripheral walls having extensions that are adapted to be connected to adjacent ones of the peripheral walls.

10 2. As an article of manufacture, a collapsible box comprising a bottom wall having bendable edge portions, peripheral side walls disposed in sidewise relation to the bottom wall, means for embracing the outer edges of the side walls and the corresponding edges 20 of the bottom wall and extending substantially the full length thereof, the side walls being adapted to be positioned at a relatively wide angle to the bottom wall by bending the edge portions of the bottom wall downwardly.

25 3. As an article of manufacture, a collapsible box comprising a bottom wall having bendable edge portions, peripheral side walls disposed in sidewise relation to the bottom wall, channel members for embracing the outer edges of the side walls and the corresponding edges of the bottom wall and extending substantially the full length thereof, the side walls being adapted to be positioned 30 at a relatively wide angle to the bottom wall by bending the edge portions of the bottom wall downwardly.

40 4. As an article of manufacture, a collapsible box comprising a bottom wall having bendable edge portions, peripheral side walls disposed in sidewise relation to the bottom wall, channel members for embracing the outer edges of the side walls and the corresponding edges of the bottom wall and extending substantially the full length thereof, the side walls being adapted to be positioned 45 at a relatively wide angle to the bottom wall by bending the edge portions of the bottom wall downwardly, and means for securing together the adjacent side walls in such angular relation to the bottom wall.

50 5. A device of the character set forth comprising a metallic bottom wall, U-shaped channel members embracing substantially the entire edge portions of said wall, and peripheral walls disposed in sidewise relation to the bottom wall and having their bottom edges disposed within said channel members whereby the peripheral walls may be positioned 55 at a relatively wide angle to the bottom wall by bending the edge portions of the bottom wall downwardly.

In testimony whereof, I hereunto affix my signature.

ROBERT A. GORSUCH.
